DETERGENT COMPOSITIONS

Irving Joseph Krems, Fort Lee, N. J., assignor to
 Colgate-Palmolive Company, Jersey City, N. J.,
 a corporation of Delaware

No Drawing. Application March 14, 1951,
 Serial No. 215,641

20 Claims. (Cl. 252—137)

1

The present invention relates to new synthetic detergent compositions, and, more particularly to compositions of the type of the anionic sulfated and sulfonated detergents having improved properties, and to a process of preparing same.

There has been a considerable amount of research to discover substances or additives which aid the efficiency of detergent compositions. The problem is exceedingly complex, however, in view of the various physico-chemical mechanisms or properties and the like involved in the action of a detergent composition including suspension, interfacial tension, micellar structure, dispersion, foam stability, etc. and the general difficulty usually in determining the particular mechanism which is being altered by changes in the formulation of detergent compositions.

During recent years, synthetic detergents of the type of the organic sulfates and sulfonates have been developed which have properties which render them highly advantageous for certain uses. In general, the exploration for suitable additives or builders for synthetic detergent compositions of the type of the anionic sulfates and sulfonates has been directed by the requirements of increased foaming and/or detergative power. While the exact relationship, if any, between foaming and detergency is not known, it is highly desirable that these detergent compositions exhibit excellent foaming properties, in addition to a high level of detergative efficiency, particularly for consumer appeal and certain home and industrial uses. In view of the complex nature of both the foam and detergency phenomena, the character of such non-soap synthetic detergents, and the many other variables in detergent compositions, additives in general exhibit a certain degree of specificity of action.

The alkyl sulfonamide type compounds have been employed as intermediates in the manufacture of detergents, wetting agents, textile softening agents, etc.

It has now been discovered that the presence of a minor proportion of a higher alkyl sulfonamide in detergent compositions consisting essentially of the anionic sulfated and sulfonated detergents is effective in achieving a significant and synergistic enhancement in surface-active properties such as detergency and foaming. In a more specific aspect, the present invention relates to built detergent compositions consisting essentially of the water-soluble sulfated or sulfonated detergents, water-soluble polyphosphate material, and a minor proportion of a higher alkyl substituted primary sulfonamide

2

as an organic builder to enhance the action of the detergent composition in aqueous solution. These improvements are unique since such sulfonamides by themselves have poor foaming or deterging properties, and thus are of little value as cleansing agents per se.

The enhancing additives of the present invention are characterized by their generally limited water solubility. More particularly, these additives may be represented by the formula:

15 wherein R is a higher alkyl group, and Y and Z individually are selected from the group consisting of hydrogen and lower alkyl.

The higher alkyl substituent may be branched or straight-chain in structure; it comprises moreover such groups as octyl, decyl, dodecyl, keryl, pentadecyl, hexadecyl, mixed long-chain alkyls derived from long-chain fatty materials, cracked paraffin wax olefins, polymers of mono-olefins, etc. This higher alkyl substituent will generally be from about 8 to about 18 carbon atoms, and preferably from about 12 to about 16 carbon atoms.

Included within the ambit of the invention is the following preferred class of compounds suitable as additives which may be represented by the structural formula:

wherein R has the significance set forth above.

35 Suitable examples of such compounds are octyl sulfonamide, decyl sulfonamide, dodecyl sulfonamide, cocyl sulfonamide wherein the "cocyl" substituent is a mixture of essentially long-chain alkyls derived from mixed coconut oil fatty acids, dodecyl sulfonamide wherein the dodecyl group is derived from a propylene tetramer, tetradecyl sulfonamide, pentadecyl sulfonamide wherein the pentadecyl group is derived from a propylene pentamer, hexadecyl sulfonamide, etc.

An additional suitable class is the polyalkyl substituted sulfonamides wherein one alkyl group is long-chain in structure as indicated, and the one or more remaining alkyl groups is lower alkyl in structure. The lower alkyl groups should have a total generally of not in excess of about six carbon atoms. It is preferred that each lower alkyl group be not in excess of about three carbon atoms each. Thus other suitable additives are:

55 (a)

wherein R has the significance set forth above and Y is a lower alkyl group, preferably containing from about 1 to about 3 carbon atoms. Examples of suitable compounds are dodecyl N-methyl sulfonamide, keryl N-methyl sulfonamide, dodecyl N-butyl sulfonamide, tetradecyl N-ethyl sulfonamide, dodecyl N-propyl sulfonamide, etc.

(b)

wherein R is as described above, and Y and Z may be the same or different, each being selected from the group consisting of lower alkyl. As exemplary of this sub-class are dodecyl N-dimethyl sulfonamide, dodecyl N-diethyl sulfonamide, keryl N-diethyl sulfonamide, dodecyl N-diisopropyl sulfonamide, dodecyl N-dipropyl sulfonamide, etc.

These various sulfonamide derivatives may be prepared in any suitable manner and numerous processes for their production are well known in the art.

The novel compositions of the present invention contain as the active ingredient the anionic sulfated and sulfonated detergents, including suitable mixtures thereof. Included therein are the aliphatic sulfated or sulfonated agents, such as the aliphatic acyl containing compounds wherein the acyl radical has about 8 to about 22 carbon atoms, and, more particularly, the aliphatic carboxylic ester type, containing at least about 10 and preferably about 12 to about 26 carbon atoms to the molecule. Among the aliphatic detergative compounds, it is preferred to use the sulfated aliphatic compounds having about 12 to about 22 carbon atoms. As suitable examples of aliphatic detergents may be found the sulfuric acid esters of polyhydric alcohols incompletely esterified with higher fatty acids, e. g. coconut oil monoglyceride monosulfate, tallow di-glyceride monosulfate; the long chain pure or mixed higher alkyl sulfates, e. g. lauryl sulfate, cetyl sulfate, higher fatty alcohol sulfates derived from coconut oil; the hydroxy sulfonated higher fatty acid esters, e. g. higher fatty acid esters of 2,3 di-hydroxy propane sulfonic acid; the higher fatty acid esters of low molecular weight alkylol sulfonic acids, e. g. oleic acid ester of isethionic acid; the higher fatty acid ethanolamide sulfates; the higher fatty acid amides of amino alkyl sulfonic acids, e. g. lauric amide of taurine, and the like.

It is a feature of this invention that the effects are particularly enhanced with the alkyl aryl sulfonate detergents. These aromatic sulfonate detergents are also known in the art. They may be mononuclear or polynuclear in structure. More particularly, the aromatic nucleus may be derived from benzene, toluene, xylene, phenol, cresols, naphthalene, etc. The alkyl substituent on the aromatic nucleus may vary widely, as long as the desired detergent power of the active ingredient is preserved.

More specific examples of suitable alkyl aromatic sulfonate detergents are the higher alkyl aromatic sulfonates. The higher alkyl substituent may vary in the manner described for such groups in the higher alkyl sulfonamide additives. Thus, it may be branched or straight-chain in structure, and comprise decyl, dodecyl, keryl, mixed long-chain alkyls from polymeric lower mono-olefins, etc. Preferred examples of this class are the higher alkyl mononuclear aryl sul-

fonates wherein the alkyl group is about 8 to about 22, and preferably about 12 to about 18 carbon atoms. More particularly it is preferred to use the higher alkyl benzene sulfonates where in the higher alkyl group averages about 12 to about 16 carbon atoms. For example, propylene may be polymerized to the tetramer and condensed with benzene in the presence of a Friedel-Crafts catalyst to yield essentially the dodecyl benzene derivative which is suitable for sulfonation to the desired sulfonate compounds.

These various anionic detergents are generally used in the form of their water-soluble salts, such as the alkali metal, alkaline earth metal, ammonium, amine, and alkylolamine salts. While the sodium, potassium, ammonium and alkylolamine (e. g. mono-, di-, and triethanolamine) salts are preferred ordinarily, other salts such as the lithium, calcium, and magnesium salts may be used if desired. For general use, it is ordinarily preferred to use the sodium and potassium salts. For certain specialized uses, it may be preferred to select the ammonium and alkylolamine salts in view of their generally greater solubility in aqueous solutions. The concentration of these water-soluble salts (including suitable mixtures thereof) in the detergent compositions of the present invention is generally at least about 10% by weight of total solids, and preferably from about 10-50%. With built compositions, particularly in particulate form, an active ingredient content of 10-50%, and preferably about 15-40% yields highly satisfactory results. Compositions with very high concentration of these active ingredients e. g. 90% of total solids, are prepared for specialized uses generally.

The amount of the sulfonamide additives in the detergent composition is generally minor in proportion to the weight of the active ingredient and effective in producing the desired improvements in detergative capacity and/or foaming power. Generally, the proportion by weight of active ingredient to additive should be from about 50:1 to about 2:1. It is preferred that the additive be from about 5 to about 30% of the active ingredients. In particulate detergent compositions the additive will usually be from about 1/2 to about 15% by weight of the detergent composition. Particularly effective results have been achieved wherein the additives are present in amounts of the order of about 1 to 10% of the total detergent composition. It is preferred usually to use about 1-5% of additive however. The optimum amount of additive and its ratio to the active ingredients will vary according to the specific detergents, the field of application and contemplated manner of use.

It has been found that particularly desirable effects are obtained with such additives in "built" synthetic detergent compositions consisting essentially of the synthetic detergents and the water-soluble polyphosphate salts. These salts have the property of inhibiting precipitation of calcium material and the like in aqueous solution and may be considered as derived from orthophosphoric acid or the like by the removal of water, though any suitable means of manufacture may be employed if desired. These molecularly-dehydrated polyphosphate salts may be wholly or partially neutralized, such as the alkali metal or ammonium salts of tripolyphosphoric, tetraphosphoric, and pyrophosphoric acids. Suitable examples are sodium tripolyphosphate ($Na_5P_3O_{10}$), potassium tripolyphosphate, tetrasodium pyrophosphate, hexasodium hexa-

5

metaphosphate (Graham's salt), hexasodium tetraphosphate, etc.

With such compositions, it is preferred that the synthetic detergent be about 10 to about 50% and usually about 15 to about 40%, and about 10 to about 80% and usually about 20 to about 60% of these water soluble polyphosphates, preferably tripolyphosphate, the above percentages being by weight of total solids of the detergent compositions, with an effective amount of the 10 organic additive described above.

The organic additives may be incorporated with active ingredient and any other ingredients at any point during the manufacturing process at which subsequent operations will not adversely modify the properties of the detergent compositions. A variety of procedures which have proved to be convenient, economical, and productive of best results are: the additives may be added to a hot aqueous slurry of about 40 to 50% solids concentration comprising the active ingredient with vigorous stirring to form a smooth, uniform and homogeneous paste, the additives may be dissolved in a suitable solvent and added to the slurry of the active ingredient, or a mixture or emulsion of the additives in water with a minor proportion of the active ingredient may be incorporated into the slurry.

Thereafter, these compositions may be prepared in the form of solutions, pastes or as dry or partially hydrated solid products, preferably in a finely divided condition. It is preferred to prepare the products in particulate form. Accordingly, the slurry of the detergent composition may be subjected to any suitable drying operations and converted to particle form. The mixture may thus be subjected to conventional spray-drying, roll-drying or drum-drying operations utilizing temperatures above about 212° F. to obtain homogeneous detergents particles.

It is common to employ various adjuvant materials in synthetic detergent compositions. The detergent compositions of the present invention may include any of these substances employed by the art in admixture with such detergent compositions generally, provided the use of any such materials does not completely neutralize or remove the effect of the sulfonamide type additives in the relationship set forth. These adjuvant builders or additives may be inorganic or organic in structure and may be mixed with the active ingredient in any suitable manner. Such convenient inorganic builders or additives as the various alkali metal phosphates (e. g. tri-sodium phosphate), the alkali metal silicates, sulfates, carbonates, etc. may be employed in these compositions. Suitable organic materials such as sodium carboxymethylcellulose may also be employed herein.

The following examples are additionally illustrative of the nature of the present invention and it will be understood that the invention is not limited thereto:

EXAMPLE I

A detergent composition is prepared by mixing on a weight basis 20% sodium dodecyl benzene sulfonate (the dodecyl group being derived from a propylene tetramer), 40% sodium tripolyphosphate, 3% sodium carbonate, 2% lauryl sulfonamide, and the balance essentially sodium sulfate.

This composition in 0.25% concentration in soft water is subjected to repeated laundering and dishwashing operations in comparison with simi-

5

lar operations conducted with the same composition without the lauryl sulfonamide. In each case, it may be noted that the foam of the detergent composition containing the sulfonamide exhibits greater volume, stability, creaminess and consistency, in comparison to otherwise identical compositions not containing the sulfonamide.

6

A detergent composition is prepared by the procedure of Example I with the modifications that the lauryl sulfonamide is 4% by weight, with a correspondingly lowered sodium sulfate content. This composition similarly exhibits improved foaming power.

EXAMPLE II

A detergent composition is prepared by the procedure of Example I with the sulfonate detergent 25% by weight and only 24% sodium sulfate. This composition in 0.25% concentration in hard water of 300 p. p. m. hardness similarly exhibits better stability, consistency, etc. during laundering and dishwashing in comparison to a "blank" run without the 2% sulfonamide.

EXAMPLE III

A detergent composition is prepared by the procedure of Example I with the sulfonate detergent 25% by weight and only 24% sodium sulfate. This composition in 0.25% concentration in hard water of 300 p. p. m. hardness similarly exhibits better stability, consistency, etc. during laundering and dishwashing in comparison to a "blank" run without the 2% sulfonamide.

EXAMPLE IV

An improved detergent composition is prepared from 20% sodium dodecyl benzene sulfonate, 40% sodium tripolyphosphate, 38% sodium sulfate and 2% lauryl sulfonamide.

In laundering operations, this composition exhibits improved soil removal properties, even in comparison to a composition having a vastly increased sulfonate detergent content.

This improved detergents effect may be indicated by a soil removal test. The testing procedure involves the uniform soiling, washing with particular detergent compositions at 110° F. $\pm 2^\circ$ F., and drying of a large number of cotton swatches. The whiteness of the various test swatches are measured by a Hunter reflectometer. The increase in reflectance due to washing may be calculated by subtracting the average reflectivity of unwashed control samples from the washed swatches.

The following table indicates the percent increased reflectance, as a measure of improved soil removal, on cotton swatches using the detergent composition of Example IV containing 20% sulfonate detergent and 2% lauryl sulfonamide in comparison to the use of a detergent composition of 35% sulfonate detergent, 40% sodium tripolyphosphate, and 25% sodium sulfate. These tests are conducted at 0.25%, 0.4% and 0.75% concentration of the detergent compositions in soft water. The percentages listed in the table represent the percent change in whiteness reflectance using as a standard the above detergent composition containing 35% sulfonate detergent without organic additive. The + value indicates the approximate improved whiteness reflectance as a measure of improved soil removal using the composition of Example IV in comparison to the standard:

Table

Concentration of Deterg. Comp.	Percent Change in Whiteness Reflectance on Cotton Soil
0.25%	+65
0.4%	+51
0.75%	+59

The marked improvement resulting from the use of the detergent composition containing the lauryl sulfonamide is clearly evident from the data. It is apparent also that the incorporation of these additives also permits a sharp reduction in the concentration of the organic detergent per se. It may be further noted that the improved results are exhibited over a wide range of washing concentrations. This feature is significant also since it permits economy of use and allows a wide latitude as to suitable quantities which may be employed by the consumer. Furthermore, these sulfonamide additives of the present invention usually achieve an even more remarkable improvement in soil removal on woolen fabrics in comparison to the desirable effects achieved on cotton soil as disclosed supra.

EXAMPLE V

A detergent composition is prepared by forming about a 60% solids slurry containing on a solids basis about 35% sodium propylene tetramer benzene sulfonate salt, 40% tri-polyphosphate, 15% sodium sulfate, 3% lauryl sulfonamide, and the remainder minor amounts of sodium chloride, sodium hydroxide, sodium carboxymethylcellulose, etc. This slurry is agitated at about 140° F. in a conventional soap crutcher to form a homogeneous mixture. The slurry is submitted to spray-drying with heated air at a temperature of about 350° F. with a resultant moisture loss of about 40%. The resulting composition is recovered in the form of beads, and possesses a high degree of detergiving and foaming properties in aqueous solution.

EXAMPLE VI

A detergent composition is prepared according to the procedure of Example V with the modifications that the active ingredient consists essentially of the keryl benzene sulfonate salt, the organic additive is the myristyl sulfonamide, and the slurry is roll dried at about 50 lbs. steam pressure to flake form. This composition also possesses highly desirable detergiving properties.

EXAMPLE VII

A detergent composition is prepared according to the procedure of Example V from the following components: 20% sodium lauryl sulfate, 40% sodium tripolyphosphate, 38% sodium sulfate, and 2% higher alkyl sulfonamides wherein the higher alkyl groups correspond essentially to those in mixed coconut fatty acids.

EXAMPLE VIII

Another suitable detergent composition is prepared by compounding 25% sodium coconut monoglyceride sulfate, 10% diacid disodium pyrophosphate, 62% sodium sulfate and 3% dodecyl sulfonamide.

Other formulations productive of desired results are:

EXAMPLE IX

	Percent
Sodium fatty alcohol sulfates derived from reduced coconut oil acids	16
Sodium chloride	1
Sodium tripolyphosphate	38
Tetrasodium pyrophosphate	15
Sodium sulfate	27
Dodecyl sulfonamide	3

EXAMPLE X

	Percent
Sodium dodecylbenzene sulfonate	9
Sodium lauryl sulfate	10
Dodecyl and tetradecyl sulfonamide (1:1)	3
Sodium carboxymethylcellulose	0.5
Sodium carbonate	1.5
Sodium sulfate	20
Sodium tripolyphosphate	44
Tetrasodium pyrophosphate	12

EXAMPLE XI

	Percent
Higher fatty acid amides of taurine derived from coconut oil	25
Sodium sulfate	30
Sodium tripolyphosphate	42
Dodecyl sulfonamide	3

20 Certain general conclusions are apparent from the many tests which have been conducted to determine the effectiveness of the additives in the relationship set forth. The most appropriate additive and its most effective concentration for each particular sulphonated or sulphated detergent composition may suitably be determined by routine controls. In each case the intended use (e.g. soft water, rug shampoos or machine washing compositions, etc.) and the proper washing conditions should be taken into consideration in order to derive the maximum beneficial effects. 25 The term "consisting essentially of" as used in the definition of the ingredients present in the composition claimed is intended to exclude the presence of other materials in such amounts as to interfere substantially with the properties and characteristics possessed by the composition set forth but to permit the presence of other materials in such amounts as not substantially to effect said properties and characteristics adversely.

30 Although the present invention has been described with reference to particular embodiments and examples, it will be apparent to those skilled in the art that variations and modifications of this invention can be made and that equivalents can be substituted therefor without departing from the principles and true spirit of the invention.

35 Having described the invention what is desired to be secured by Letters Patent is:

40 1. A detergent composition consisting essentially of water-soluble detergent selected from the class consisting of the water-soluble anionic organic sulfate and sulfonate detergents, and a sulfonamide compound in an amount minor in proportion to said detergent and sufficient to improve the said removal power thereof, said sulfonamide represented by the formula:

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 sulfonamide compound as an organic builder represented by the formula:

wherein R is a higher alkyl group of about 8 to 18 carbon atoms and Y and Z are each selected from the class of hydrogen and lower alkyl groups, the proportion of said detergent to sulfonamide compound being from about 50:1 to about 2:1 by weight.

4. A detergent composition consisting essentially of water-soluble detergent selected from the class consisting of the water-soluble anionic organic sulfate and sulfonate detergents, and a sulfonamide compound in an amount minor in proportion to said detergent and sufficient to improve the soil removal power thereof, said sulfonamide compound represented by the formula:

wherein R is a higher alkyl group.

5. A detergent composition consisting essentially of water-soluble detergent selected from the class consisting of the water-soluble anionic organic sulfate and sulfonate detergents, about 10 to about 80% of water-soluble inorganic polyphosphate salts, and a sulfonamide compound in an amount minor in proportion to said detergent and sufficient to improve the soil removal power thereof, said sulfonamide compound represented by the formula:

wherein R is a higher alkyl group of about 8 to 18 carbon atoms.

6. A detergent composition consisting essentially of water-soluble detergent selected from the class consisting of the water-soluble anionic organic sulfate and sulfonate detergents, about 10 to about 80% of water-soluble inorganic tripolyphosphate salts, and a sulfonamide compound in an amount minor in proportion to said detergent and sufficient to improve the soil removal power thereof, said sulfonamide compound represented by the formula:

wherein R is a higher alkyl group of about 8 to 18 carbon atoms.

7. A detergent composition consisting essentially of water-soluble detergent selected from the class consisting of the water-soluble anionic organic sulfate and sulfonate detergents, and a sulfonamide compound as an organic builder represented by the formula:

wherein R is a higher alkyl group of about 8 to 18 carbon atoms, the proportion of said detergent to sulfonamide compound being from about 50:1 to about 2:1 by weight.

8. A detergent composition consisting essentially of water-soluble detergent selected from the class consisting of the water-soluble anionic organic sulfate and sulfonate detergents, and a sulfonamide compound in an amount minor in proportion to said detergent and from about 1/2 to about 15% by weight of the detergent composition, said sulfonamide compound represented by the formula:

wherein R is a higher alkyl group of 12 to 16 carbon atoms.

9. A detergent composition consisting essentially of water-soluble detergent selected from the class consisting of the water-soluble anionic organic sulfate and sulfonate detergents, and a sulfonamide compound in an amount minor in proportion to said detergent and sufficient to improve the soil removal power thereof, said sulfonamide compound represented by the formula:

wherein R is a higher alkyl group of about 8 to 18 carbon atoms and Y is a lower alkyl group of up to about 3 carbon atoms.

10. A detergent composition consisting essentially of water-soluble detergent selected from the class consisting of the water-soluble anionic organic sulfate and sulfonate detergents, and a sulfonamide compound in an amount minor in proportion to said detergent and sufficient to improve the soil removal power thereof, said sulfonamide compound represented by the formula:

wherein R is a higher alkyl group of 8 to 18 carbon atoms and Y and Z are lower alkyl groups of up to about 3 carbon atoms each.

11. A detergent composition consisting essentially of water-soluble higher alkyl aryl sulfonate detergent, and a sulfonamide compound in an amount minor in proportion to said detergent and sufficient to improve the soil removal power thereof, said sulfonamide compound represented by the formula:

wherein R is a higher alkyl group of about 8 to 18 carbon atoms.

12. A detergent composition consisting essentially of water-soluble higher alkyl mononuclear aryl sulfonate detergent, and a sulfonamide compound as an organic builder represented by the formula:

wherein R is a higher alkyl group of about 8 to 18 carbon atoms, the proportion of said detergent to sulfonamide being from about 50:1 to about 2:1 by weight.

13. A detergent composition consisting essentially of water-soluble higher alkyl benzene sulfonate detergent, and a sulfonamide compound in an amount minor in proportion to said detergent and from about 1/2 to about 15% by weight of the detergent composition, said sulfonamide compound represented by the formula:

wherein R is a higher alkyl group of about 12 to 16 carbon atoms.

14. A detergent composition consisting essentially of water-soluble higher alkyl benzene sulfonate detergent, about 10 to about 80% of water-soluble inorganic polyphosphate salts and a sulfonamide compound as an organic builder represented by the formula:

wherein R is a higher alkyl group of about 8 to 18 carbon atoms, the proportion of said detergent to sulfonamide being from about 50:1 to about 2:1 by weight.

11

15. A detergent composition consisting essentially of water-soluble aliphatic sulfate detergent and a sulfonamide compound in an amount minor in proportion to said detergent and sufficient to improve the soil removal power thereof, said sulfonamide compounds represented by the formula:

wherein R is a higher alkyl group of about 8 to 18 carbon atoms.

16. A detergent composition consisting essentially of water-soluble higher alkyl sulfate detergent and a sulfonamide compound in an amount minor in proportion to said detergent and from about $\frac{1}{2}$ to about 15% by weight of the detergent composition, said sulfonamide compound represented by the formula:

wherein R is a higher alkyl group of about 12 to 16 carbon atoms.

17. A detergent composition consisting essentially of water-soluble higher fatty acid monoglyceride monosulfate detergent, and a sulfonamide compound in an amount minor in proportion to said detergent and from about $\frac{1}{2}$ to about 15% by weight of the detergent composition, said sulfonamide compound represented by the formula:

wherein R is a higher alkyl group of about 12 to 16 carbon atoms.

18. A detergent composition consisting essen-

12

tially of water-soluble detergent selected from the class consisting of water-soluble anionic organic sulfate and sulfonate detergents, and dodecyl sulfonamide in an amount minor in proportion to said detergent and sufficient to improve the soil removal power thereof.

19. A detergent composition consisting essentially of water-soluble detergent selected from the class consisting of water-soluble anionic organic sulfate and sulfonate detergents, and lauryl sulfonamide in an amount minor in proportion to said detergent and from about $\frac{1}{2}$ to about 15% by weight of the detergent composition.

20. A detergent composition consisting essentially of water-soluble higher alkyl benzene sulfonate detergent, and lauryl sulfonamide in an amount minor in proportion to said detergent and sufficient to improve the soil removal power thereof.
